UNITED STATES PATENT OFFICE.

JOHN W. ANDERSON, OF GARY, INDIANA.

INDICATOR FOR COOLING SYSTEMS.

Application filed March 28, 1927. Serial No. 178,992.

My invention relates broadly to indicating devices and particularly to indicating devices of the type shown and described in my co-pending application, Serial No. 111,345 filed 5 May 24, 1926.

Particular objects of my invention are to provide an improved device of the kind described for indicating the conditions obtaining within the cooling system of an internal 10 combustion engine; to provide an improved device of the kind described adapted to be mounted upon the filling tube of an automobile radiator and constructed so that it may be quickly and easily detached therefrom; to 15 provide an improved device of the kind described which cooperates with the overflow tube of the radiator and is so constructed that it may be connected thereto with very little effort; to provide a device of the kind described which is relatively simple in construction and is so formed that it tends to prevent 20 the waste of cooling liquid through the overflow tube, and to provide a device of the kind described which will give a distinctive signal 25 when steam alone is being discharged rapidly through the overflow tube.

Apparatus embodying my invention is adapted to give a series of signals which resemble the signals given by the apparatus 30 shown and described in the aforementioned co-pending application, the signals being such that the operator of the automobile or other vehicle is warned in advance of eminent wastage of cooling liquid because of over-heating and is also warned when such wastage is in progress.

Many other objects and advantages of the construction herein shown and described will be obvious to those skilled in the art from 40 the disclosure herein given.

To this end my invention consists in the novel construction, arrangement and combination of parts herein shown and described, and more particularly pointed out in the 45 claims.

In the drawings, wherein like reference characters indicate like or corresponding parts:

Fig. 1 is a central vertical section taken 50 through a device embodying my invention, the improved device being shown mounted upon a filling tube of an automobile radiator; 55 Fig. 2 is a section taken on line 2—2 of Fig. 1; 60 Fig. 3 is a section taken on line 3—3 of Fig. 1; 65 Fig. 4 is a section taken on line 4—4 of Fig. 1.

Referring to the drawings, I have shown a device embodying a preferred form of the 60 invention, the device being shown mounted upon the filling tube of a radiator which is of the type commonly employed in automobiles, or the like. Only a fragmentary portion of the radiator is shown as the invention 65 does not relate to the construction thereof. The radiator is identified by the reference character 10 and the filling tube is shown at 12. In accordance with the usual construction, the radiator 10 is provided with an 70 overflow tube 14, the upper end of which is centrally disposed in the filling tube 12 and the lower end of which preferably communicates with the atmosphere. The upper end of the filling tube 12 is normally closed by a 75 cap 15 which is preferably cast and is provided, in this instance, with inserts 16 and 17. The insert 17 is preferably provided with a screw-thread 18 whereby the cap may be detachably secured to the filling tube and 80 the insert 16 is preferably provided with screw-threads 19 for a purpose which will 85 presently appear.

Formed in the cap 15 is a substantially central aperture 22 which is enlarged at its lower 90 end as indicated at 23 to provide an annular shoulder 24 against which a packing ring 25 is adapted to seat. Projecting through the aperture 22 is a hollow member or dome 27 which is preferably formed from glass or 95 other transparent material, the member 27 being open at its lower end and being provided with an annular flange 29. Engaging the lower end of the glass member 27 is a packing ring 30 and disposed immediately below 100 the packing ring 30 is a washer 32 which is centrally apertured as at 37 to accommodate a tube 38. As best shown in Fig. 1, the central portion of the washer 32 is struck up to provide a relatively shallow annular pocket 39 adjacent the inner surfaces of the packing ring 30 and it will be noted that the washer is provided with apertures 40 through which 105 fluid may enter the glass member 27 and thence pass down through the tube 38 into the overflow tube 14 which communicates with the lower end of the tube 38. The packing rings 25 and 30, the flange 29 of the glass member 27 and the washer 32 are secured in place in the enlarged portion 23 of the aperture 22 by a nut 42 which engages the screw-threads 19 provided upon the insert 16.

A packing ring 44 seated upon the upper end of the filling tube 12 supports the outer edge of a circular plate 45 which in turn, supports a spring washer 46, the spring washer 46 being inserted between the plate 45 and the bottom surface of the cap 15. The plate 45 is provided with a central aperture 47 which accommodates the tube 38. Intermediate the outer edge of the plate 45 and the aperture 47, the plate is formed to provide an annular pocket 50. The plate is preferably provided with apertures 52 and 53 through which fluid may pass from the filling tube 12 up into the glass member 27 by way of the apertures 40 provided in the washer 32. Obviously, when steam or liquid passes up through the apertures 52, 53 and 40, some liquid will collect in the pockets 39 and 50.

The tube 38 fits snugly in the central aperture provided in the circular plate 45 so that the vibration of the vehicle does not tend to displace the tube relative to the plate. To prevent the tube 38 from being driven up into the glass member 27 an undesirable distance, the tube is preferably provided with an outwardly extending annular bead 55 engageable with the under surface of the circular plate 45. It will be also noted that the lower end of the tube 38 is flared outwardly as at 56 so that the tube may be readily pushed over the end of the overflow tube 14. The construction is such that the cap 15, the glass member 28 and the washer 35 may be removed as a unit from the filling tube 12 after which the spring washer 46 and the circular plate 45, together with the tube 38, may be lifted from the upper end of the filling tube. After the supply of cooling liquid has been replenished, the circular plate 45 may be positioned again upon the packing ring 44 in such manner that the flared end 56 of the tube 38 will receive the upper end of the overflow tube 14. The cap 15, together with the glass member 27 and the washer 32, may then be screw-threaded upon the filling tube, the spring washer 46 being inserted between the cap and the circular plate.

The operation of the above described indicating device is substantially as follows: Assuming that there is a plentiful supply of cooling liquid in the cooling system and that the automobile upon which the device is mounted, is in operation, there will be substantially no indication of any kind in the glass member 27 as long as the temperature of the cooling liquid does not approach the boiling point. However, if for any reason, the temperature of the cooling liquid approaches its boiling point, this fact will be indicated in the glass member 27 by a solid column of water which rises and falls irregularly and at times disappears from the glass member 27 until the cooling fluid boils with sufficient violence to create a high pressure within the radiator. Then a steady flow of liquid through the glass

member 27 will be observed, this liquid being discharged from the cooling system by way of the overflow tube 14. If the driver of the automobile heeds the warning and corrects the condition which causes it, the boiling ceases and the pressure within the radiator falls. The liquid disappears from the glass member 27 and returns to the radiator in an unbroken column. However, if the driver does not heed this warning and permits a relatively large amount of cooling liquid to waste through the overflow tube 14, a mixture of steam and liquid will be observed in the glass member 27, the liquid and steam churning in such manner that they are readily observed in the glass member. This churning continues until substantially all of the cooling liquid has been discharged from the radiator. When sufficient cooling liquid has been wasted so that more steam than liquid passes through the glass member 27, the steam will pick up liquid which has accumulated in the pockets 39 and 50 and this liquid will form a dancing film upon the interior surface of the glass member 27, which dancing film will be readily observable to the driver of the vehicle.

As set forth in my aforementioned copending application, the improved device indicates four definite and significant stages through which the cooling fluid passes and it is imperative that the driver corrects the abnormal condition under which the engine is operating before the fourth stage has obtained for any appreciable length of time for otherwise serious damage will be done to the engine. The four stages are as follows:

The first stage: from atmospheric temperature to normal operating temperature. During this stage, the glass member remains substantially clear.

The second stage: from normal operating temperature to simmering temperature which precedes active boiling. An unbroken column of liquid will rise and fall in the glass member 27.

The third stage: from simmering temperature creating comparatively slight pressure to active boiling which causes substantially continuous wastage of cooling liquid because of the comparatively high steam pressure created in the radiator. The glass member 27 becomes completely filled with an unbroken column of liquid flowing therethrough and wastes through the overflow tube 14.

The fourth stage: from active boiling and wasting from the still adequate reserve supply of cooling liquid to a comparatively super-heated steaming and wasting of a boiling liquid. When this condition obtains, the glass member 27 shows violent churning steam and water passing therethrough.

The signals given by the device embodying the present invention differ somewhat from the signals given by the device shown in

my aforementioned copending application. Thus, it appears that the period during which the solid column of air rises and falls in the glass member 27 is considerably shorter than the period during which the water rises and falls in the similar member provided in the device shown in my copending application.

The washer 32 and the circular plate 45 serve as bevels and tend to retard the waste of cooling liquid or fluid through the overflow tube 14. This is advantageous in that in many instances, it is extremely desirable to conserve the supply of cooling liquid as it can not be readily replenished.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. An indicating device of the kind described comprising an apertured closure member for the filling opening of an automobile radiator provided with an overflow pipe, a substantially transparent hollow member mounted on said closure member and arranged to communicate with the interior of said radiator, means whereby vapor and liquid may flow from said hollow member into said overflow pipe, and means forming a pocket for collecting condensate from said hollow member, said pocket being so positioned that vapor passing upwardly through said hollow member will carry a portion of the condensate with it.

2. An indicating device of the kind described comprising an apertured closure member for the filling opening of an automobile radiator provided with an overflow pipe, a substantially transparent hollow member mounted on said closure member and arranged to communicate with the interior of the radiator, means serving as a baffle to retard the flow of vapor and liquid from the

interior of said radiator into said hollow member, said baffle means having a pocket formed therein to collect condensate from said hollow member, and means whereby vapor and liquid may be discharged from said hollow member into said overflow pipe.

3. An indicating device of the kind described comprising an apertured closure member for the filling opening of an automobile radiator provided with an overflow pipe, a substantially transparent hollow member mounted to be visible above said closure member and arranged to communicate with the interior of said radiator through said closure member, a tube concentrically disposed with respect to said closure member and arranged to project into said hollow member, said tube being adapted to telescope upon the upper end of said overflow pipe and being adapted to discharge fluid into said overflow pipe, and means disposed around said tube and arranged to retard the flow of fluid from the interior of said radiator up into said hollow member.

4. An indicating device of the kind described comprising an apertured closure member for the filling opening of an automobile radiator having an overflow pipe, a substantially transparent hollow member mounted on said closure member and arranged to communicate with the interior of said radiator, a plate disposed below said hollow member and provided with a plurality of apertures including a central aperture, said plate serving as a baffle to retard the flow of vapor and liquid from said radiator into said hollow member, and a tube projecting through said central aperture into said hollow member, said tube being engageable with the upper end of the overflow pipe and being provided with means cooperating with said plate for preventing the tube from being projected an undesirable distance into said hollow member.

In testimony whereof, I have hereunto signed my name.

JOHN W. ANDERSON.
